UNITED STATES PATENT OFFICE.

SAMUEL EDELMAN, OF PHILADELPHIA, PENNSYLVANIA.

DESIGN FOR A LIGHTING FIXTURE.

Application filed September 8, 1926. Serial No. 19,005. Term of patent 3½ years.

To all whom it may concern:

Be it known that I, SAMUEL EDELMAN, a citizen of the United States, residing in the city of Philadelphia, county of Philadelphia, and State of Pennsylvania, have invented a new, original, and ornamental Design for a Lighting Fixture, of which the following is a specification, reference being had to the accompanying drawing, forming part thereof.

In the drawing, the figure is a perspective view of a lighting fixture showing my new design.

I claim:

The ornamental design for a lighting fixture as shown.

SAMUEL EDELMAN.
